UNITED STATES PATENT OFFICE.

FRANK DELLA TORRE, OF BALTIMORE, MARYLAND.

STOPPER-FASTENER.

SPECIFICATION forming part of Letters Patent No. 340,257, dated April 20, 1886.

Application filed February 9, 1886. Serial No. 191,270. (No model.)

To all whom it may concern:

Be it known that I, FRANK DELLA TORRE, a citizen of the United States, residing at Baltimore, in the State of Maryland, have invented 5 certain new and useful Improvements in Bottle-Stopper Fasteners, of which the following is a specification, reference being had therein to the accompanying drawings.

This invention has relation to bottle-stopper fasteners, and more particularly to that class 10 of fasteners that comprise a neck-wire, a lever, and a bail, the former secured about the neck of the bottle, and the latter connected with the stopper and with the lever, which is pivotally connected with the neck-wire; and the 15 objects of the invention are to lock the bail against accidental displacement after being operated upon by the lever, to firmly hold the stopper in the mouth of the bottle, and to provide a construction and co-operation of the 20 parts that will give a straight draft of the bail upon the stopper when the bottle is closed, thereby avoiding the necessity of causing the free end of the bail to pass by the center of 25 the pivot of the lever, and to accomplish these by a lever so formed and operating as to be capable of serving its function of closing the bottle by a downward stroke or movement of the hand of the bottler.

30 Other objects and advantages will appear in the following description of the invention, in which reference is made to the accompanying drawings, in which—

Figure 1 is a side elevation of a portion of a bottle provided with my fastener, shown in 35 a closed and locked position. Fig. 2 is a similar view of the same, with parts in an unlocked position, the dotted line showing the bail swung down. Fig. 3 is a side elevation showing a 40 lever of increased length. Fig. 4 is a rear elevation, the parts being in a closed position. Fig. 5 is a plan of the neck-wire, and Fig. 6 a perspective of the lever.

Like parts in all the figures are indicated by 45 like letters of reference.

A represents the bottle, B the stopper, G the neck-wire, D the bail, and E the lever.

The stopper may be of any desired construction involving an eye, B', through which the 50 bail passes. In this instance said eye is formed as a part of a metallic stopper-foundation, B'',

seated in a rubber packing, B³, adapted to fit the mouth of the bottle and to be compressed therein when the bail is locked in a closed position. The free ends of the bail D are bent 55 inwardly, to form pintles D', which enter eyes E', formed in the lever E, whereby a pivotal connection of the bail and lever is provided. As usual in the construction of bottle-fasteners, it is apparent that the pintles and eyes 60 may be reversed in relative position—that is to say, the pintles may be formed on the lever and the eyes on the bail. The neck-wire G may also be of any usual construction; but in this instance I have formed the same of a single piece, the wire being bent upon itself to form a horn, lug, or pintle, G', and then curved in a substantially-semicircular form, as at G², to embrace the neck of the bottle, said portions G² being bent at their ends G³, 70 to constitute an opposite horn, lug, or pintle.

As stated in regard to the bail, so, also, in constructing the neck-wire, instead of forming horns or pintles thereon, eyes may be formed to receive pintles formed on the lever in lieu 75 of eyes, as hereinafter described, whereby a pivotal connection of the lever and neck-wire is secured.

As shown in Fig. 5, the pintles of the neck-wire are diametrically opposite each other, 80 whereby the bail exerts other than a direct draft upon the stopper when the bottle is closed; but by making one-half of the neck-wire to embrace more than one-half of the bottle-neck the pintles G' G³ are thrown sufficiently one side to bring the bail in a direct line, (indicated by the dotted line x, Fig. 1,) whereby a straight draft is secured. This arrangement is possible by reason of the novel features of my invention hereinafter described. 85 90

Again referring to Fig. 5, it will be noticed that the lugs or pintles G' G³ are beveled, tapered, or pointed, as at G⁴, for a purpose hereinafter stated.

The lever is extended beyond the eyes E' 95 thereof, to form eyes E'', and the extreme ends of the wire of which the lever is composed are extended beyond the eyes E'' and projected outwardly to form stops E''.

Now, it will be noticed that when the parts 100 are connected together, as shown, (that is, with the eyes E'' mounted upon the lugs G' G³ of the

neck-wire and the lever E pivotally connected to the bail at the eyes E', by depressing the lever from the position shown in Fig. 2 to that shown in Fig. 1, the stopper is drawn into the mouth of the bottle and the bail swings in the eye B' of the stopper as a center, against the beveled ends of the pintles of the neck-wire, and passes over and by said beveled ends and comes into contact with the stops E³ on the lever. In passing by the ends of the pintles of the neck-wire the bail at each side of the bottle springs outwardly, as indicated by dotted lines in Fig. 4, after which it returns to its normal position and rests between said pintles and the stops E³ of the lever, so that said bail cannot by ordinary accident be forced in either direction to release the stopper.

In the modification illustrated in Fig. 3 I have lengthened the lever E, so that instead of striking against the upper part of the bottle, as shown in Fig. 2, it passes over the bottle, the object being to permit the stopper to be swung away from the mouth at either side of the bottle and to such a distance as will permit of the stopper being completely rotated upon the bail, as indicated by dotted lines y, Fig. 3, whereby the necessity of care in presenting a bottle to a machine to be filled does not exist, from the fact that the stopper may be placed in position from either side, when a simple downward movement of the hand of the bottler serves to force the lever down and lock the stopper in position, the bottler's hand being in position to give that movement at the completion of the operation of placing the stopper in position. This advantage does not exist in that class of stopper-fasteners wherein the lever locks with an upward motion, and though apparently slight, is in the end important, from the fact that rapid bottling requires a minimum number of motions upon the part of the bottler.

By providing the neck-wire with a stop to act upon the bail at one side and the lever with a companion stop to operate upon the bail at an opposite side, whereby when the bail is locked it rests between said stops, I also prevent any necessity of bringing the bail into actual

contact with the neck of the bottle, either when in a locked closed position or in the operation 50 of locking and closing the same. This effect of keeping the bail from contact with the neck of the bottle is secured without the provision of stops on the neck-wire when the parts are arranged to pass the center, as shown in Fig. 1. 55

Having described my invention and its operation, what I claim is—

1. The combination of a bail, a neck-wire constructed to act upon one side of the bail as a stop and a lever constructed to act at the 60 opposite side of the bail as a stop, substantially as specified.

2. The combination of a neck-wire, a bail, and a lever, the neck-wire and lever being provided with stops and the bail being adapted 65 to spring into a locked position between the stops, substantially as specified.

3. The combination of a bottle, a bail, neck-wire, and lever, the latter constructed to project from the bottle-neck and out of contact 70 therewith when the bail is locked, and provided with a stop to act upon one side of the bail, and the neck-wire having a stop to act upon the opposite side of the bail, substantially as specified.

4. A neck-wire constructed of a single piece 75 and provided with beveled pintles projected to form stops which permit the passage of a bail in both directions, substantially as specified.

5. In a stopper-fastener, the lever E, provided at each of its ends with the eyes E' E' and 80 the stops E³, substantially as specified.

6. The combination of the bottle A, stopper B, bail D, a neck-band, G, and lever E, having the stop E³, substantially as specified.

7. The combination of the bottle A, stopper B B' B³, the bail D, having pintles D', neck-wire G, having the pintles G' G³, and the lever E, having the eyes E' E' and stops E³, substantially as shown and described.

In testimony whereof I affix my signature 90 in presence of two witnesses.

FRANK DELLA TORRE.
